US00D706571S

(12) United States Design Patent
Rivera et al.

(10) Patent No.: US D706,571 S
(45) Date of Patent: * Jun. 10, 2014

(54) COOKING GRILL

(71) Applicant: Tropitone Furniture Co., Inc., Irvine, CA (US)

(72) Inventors: Richard Rivera, Corona, CA (US); Brian Adam Mehler, Long Beach, CA (US)

(73) Assignee: Tropitone Furniture Co., Inc., Irvine, CA (US)

() Term: 14 Years

(21) Appl. No.: 29/465,809

(22) Filed: Aug. 30, 2013

Related U.S. Application Data

(63) Continuation-in-part of application No. 29/431,050, filed on Aug. 31, 2012, now Pat. No. Des. 695,059.
